UNITED STATES PATENT OFFICE.

EDWIN L. WALLACE, OF NIAGARA FALLS, NEW YORK, ASSIGNOR TO THE SHREDDED WHEAT COMPANY, OF NIAGARA FALLS, NEW YORK, A CORPORATION OF NEW YORK.

CHAIN TIGHTENER.

Application filed April 12, 1922. Serial No. 552,039.

Figure 1 is a side view of the invention as applied.

Figure 2 is a detail end view of the gearing connections.

5 Figure 3 is a detail plan view of the same.

The invention has relation to means for tightening or taking out the slack from endless conveyor chains or belts, the object 10 being to provide improved means for automatically taking out the slack of or tightening an endless conveyor such for instance as shown in the co-pending application of W. H. Aydelotte, for oven and drier S. No. 15 560,173, filed May 11, 1922, wherein each stretch of the conveyor chain is quite long, seventy feet in fact, and wherein there are twelve stretches, the conveyor chain being subjected to considerable temperature 20 changes in the oven inclosure as compared with the temperature of the chain in the portion thereof outside of said inclosure, and to temperature changes in the oven inclosure itself, rendering it necessary to provide some automatic means for the purpose 25 stated that will be efficient and reliable.

The invention consists in the novel construction and combinations of parts as hereinafter set forth.

30 In the accompanying drawings illustrating the invention, the numeral 1', designates the frame of the oven inclosure, 1 is the conveyor chain, bearing the trays 3; 2 are the sprocket wheels around which the chain travels; 5 are the journal boxes wherein the shafts of said sprocket wheels have bearings and 6 are horizontal tracks in the framing wherein said boxes may have movement to regulate the tension of the conveyor chain, 35 as will appear.

The journal boxes 5 at one end portion of the oven are held stationary under the control of tension regulating screws 7, but at the other or far or rear end of the oven, the 45 boxes 5 are engaged by longer tension regulating screws or rods 8 engaging perforations 9 of the framing and having threaded thereon each a nut 10, a coiled spring 11 surrounding the rod and bearing at one end 50 thereof against said nut and at the other end thereof against the framing at 12, whereby the box 5 has tension constantly

exerted thereon by the spring 11 to take up slack in the conveyor chain.

The floating sprocket wheels 2 at the far end of the oven are driven individually by sprocket gearing 13, including wheels 14 upon transverse shafts 15, the latter in vertical series and having spur gear driving connections 16 also in vertical series, one 60 series at each side, the driving connections being in duplicate to insure a balanced action.

In the vertical series of spur gears 16, intermediate spur gears 16' are used in train 65 between the spur gears 16 to properly transmit the driving movement to the sprocket wheels being driven, i. e. in order that the several stretches of the conveyor chain shall be given the proper direction of movement. 70

It will be observed that while by the arrangement above described each double stretch of the conveyor chain is individually driven, the take-up for the several stretches will be equalized, so that the tension upon 75 each of the springs 11 will be the same. The equalizing action of the springs will be assisted by the drive itself, since any lengthening of a double stretch of the conveyor chain by outward movement of a driven 80 sprocket 2 will tend to slacken the drive chain of the related gearing 13, whereupon the feeding movement of the sprocket 14 will be partially absorbed in feeding the drive chain from the working to the following stretch. Thus the speed of the driven 85 sprocket will be diminished, while the pull upon this sprocket by the unaffected drive of the next higher sprocket in series will act to restore tension to the slackened 90 spring 11.

The conveyor chain is shown as provided with means for insuring that the trays shall be maintained in true horizontal position while passing around the sprocket wheels 95 at the ends of the several stretches, as disclosed in co-pending application, S. No. 552,037 of E. P. Webster, for conveyor chain filed Apr. 12, 1922.

I claim:

1. The combination with an endless belt having a plurality of double stretches, of means for automatically taking up the slack in the several stretches and for driving the

same adapted to equalize the amount of slack taken up therein and to equalize the drive, and including a train of spur gears having separate chain and floating sprocket gear connection with each double stretch.

2. The combination with an endless belt having a plurality of double stretches, of means for automatically taking up the slack in the several stretches and for driv-

ing the same adapted to equalize the amount 10 of slack taken up therein and to equalize the drive, and including constantly acting spring tension devices and a train of spur gears having separate chain and floating sprocket gear connection with each double 15 stretch.

In testimony whereof I affix my signature.
EDWIN L. WALLACE.
